UNITED STATES PATENT OFFICE.

WILLIAM T. PIERCE, OF CAMBRIDGE, MASSACHUSETTS.

AUXILIARY POWER FOR PUMPING.

1,036,328.

Specification of Letters Patent. Patented Aug. 20, 1912.

Application filed April 25, 1912. Serial No. 693,051.

To all whom it may concern:

Be it known that I, WILLIAM T. PIERCE, a citizen of the United States, and resident of Cambridge, in the county of Middlesex and State of Massachusetts, have invented 5 certain new and useful Improvements in Auxiliary Power for Pumping, of which the following is a specification.

The object of the present invention is to 10 provide auxiliary power for a steam-driven pump.

The invention is carried out by combining 15 an electric motor and transmitting mechanism with a pump and steam engine for the pump.

The present invention does not reside in 20 any degree in the pump or the steam engine but resides in the combination with the pump of two motors which employ different power agents, such as steam and electricity, 25 and a single regulator whereby both power agents are controlled. The auxiliary motor and controlling means therefor may be combined with any suitable pump and steam engine in such manner as to render the combined apparatus capable of operating by 30 the power of the steam engine alone, or by the power of the electric motor alone, or by the combined power of the steam engine and electric motor.

The purpose for which the pump is operated is immaterial, although the combination is designed primarily for a hydraulic pump for elevator service.

The advantages of the combination are 35 hereinafter pointed out.

The accompanying drawing, which illustrates 40 one arrangement in which the elements may be combined, represents a pump, a steam engine for driving the same, an auxiliary electric motor also connected to the pump to drive the same, and automatic means for controlling the steam engine and the electric motor.

The same reference characters indicate the 45 same parts wherever they occur.

The drawing is somewhat conventional, for the purpose of avoiding unnecessary drawing, but certain features will be readily understood by persons familiar with pumping apparatus, without having them all 50 illustrated in detail.

A pump is indicated at 10, and the cylinder thereof at 11. The pump piston is indicated at 12, and the piston rod is indicated 55 at 13. The delivery pipe of the pump is in-

dicated at 14, and a storage tank is indicated at 15. The cylinder of a steam engine is indicated at 16, and the steam piston is indicated at 17, the piston being affixed to the piston rod 18. The valve mechanism for admitting steam to the cylinder 16 is indicated as a whole at 18. The steam-supply pipe is indicated at 19, and the throttle valve therefor is indicated at 20. An automatic regulator for the steam engine is indicated at 21. There are, of course, a great many styles of regulators for this purpose, and their function and operation are so well known that it is not necessary to illustrate 60 the interior or to explain their operation other than to state that when the pump has generated sufficient pressure in the storage tank the regulator 21 shuts the throttle valve 20, and that when the pressure in the tank falls the regulator automatically opens the throttle valve to start the steam engine whereby the pump is operated to restore the pressure in the storage tank. The regulator illustrated is of the diaphragm type 65 and is connected to the storage tank by a pipe 22. When the pressure in the tank is of the desired degree, the plunger 23 of the regulator is raised. This plunger is connected to a weighted arm 24 whose fulcrum is indicated at 25. The weight is indicated at 26 and is so disposed that it presses the arm 24 downwardly against the pressure on the diaphragm. As shown by the drawing 70 the arm 24 is at its lowest position, indicating that the pressure in the storage tank has fallen and that power is required to operate the pump to restore the pressure to maximum. The free end of the arm 24 is connected by a link 27 to an arm 28 of the 75 throttle valve in such manner that when the weight carries the arm downwardly the throttle valve is opened, and when the arm is raised by the diaphragm the throttle valve is closed. This mechanism and operation is 80 all well known, and I do not make any claim 85 for it *per se*.

The auxiliary electric motor is indicated conventionally at 30. The motor shaft 31 carries a driving pinion 32 whose teeth 100 mesh with the teeth of a large gear 33. This gear is affixed to a shaft 34 which is mounted in suitable bearings upon a base 35. A crank disk 36 is affixed to the shaft 34 and thus compounded with the gear 33. 110 The crank pin 37 carried by the crank disk is connected by a connecting rod 38 with

the piston rod 13 which, as shown, extends through both heads of the steam cylinder 16. A pivot stud 39 is used to connect the rod 38 with a sliding crosshead 40 at the right-hand end of the piston rod. Suitable stuffing boxes are, of course, provided for preventing the escape of steam from the cylinder 16 around the bearings of the piston rod.

10 The regulator 21 which is provided for controlling the steam engine is used also for controlling the electric motor, the control of the electric motor being accomplished through the medium of a rheostat 41 whose 15 operating arm 42 is connected by a link 43 with the weighted arm 24.

A switch is indicated conventionally at 44 for forming the desired connection with the electric feed wires which are connected to 20 the rheostat. Electric conductors 45 connect the motor 30 with the rheostat. The connection between the rheostat and the motor is such that when the controller 42 is in the position shown the full current of 25 electricity is supplied to the motor; but when the controller is raised as far as the regulator can raise it, electrical connection is broken.

The drawing is intended to represent the 30 apparatus being driven by the electric motor alone, although the throttle 20 is open. It is assumed that there is no supply of steam in the present instance and that for that reason it is immaterial whether the valve 35 20 is open or closed. The petcocks 46 at the bottom of the steam cylinder are open, thus affording open communication between the atmosphere and the interior of the steam cylinder to vent the cylinder and avoid any 40 resistance due to pressure or vacuum caused by movement of the piston 17. So long as the pressure in the storage tank is below maximum, the rheostat maintains electric connection for driving the electric motor; 45 but when the maximum pressure has been attained, the regulator will move the controller 42 and disconnect the electric motor so that the pump will stop.

If there is a supply of steam available, 50 the steam engine and electric motor may be utilized at the same time if it is desired to drive the pump at high speed. In such case the only change of parts necessary to accomplish the desired result is to close the petcocks 46. If it should be desired to operate the pump by means of the steam engine alone, the source of electrical power may be disconnected by opening the switch 55 44 or by disconnecting the link 43 from either the controller 42 or from the arm 24, leaving the controller in its upper position. The mechanical connection between the piston rod 13 and the crank 37 should likewise be broken. This may be done by removing 60 the connecting stud 39 from the crosshead

40 and by swinging the connecting rod 38 out of the path of the crosshead.

When the two motors are combined and controlled in the manner explained, the pump may be operated with great economy, according to various conditions. For example, if the pump is used for operating an elevator, the combined power of the two motors will operate the elevator at high speed. The maximum pressure which the 75 pump will develop is, of course, determined by the position of the weight 26 on the arm 24. Thus, if it is desired to have a relatively high pressure available for operating the elevator at high speed, the weight will 80 be moved toward the free end of the arm 24. On some occasions—for example, on Sundays or holidays, or at night—it may be desirable to operate the elevator at slow speed, for the sake of economy. If at such 85 times there is a sufficient supply of steam the electric motor may be disconnected, the weight 26 may be moved toward the fulcrum of the arm 24, and the pump may be operated by the steam engine alone in the 90 usual manner.

At certain times it may be desirable to discontinue the supply of steam. At night, for example, or on Sundays or holidays, the elevator may be operated more economically 95 by using the electric motor alone, in which case the services of a fireman and engineer are not necessary to keep up the supply of steam and attend to the steam engine. No attendant is necessary for the electric motor, 100 and it may be assumed that the current therefor is supplied, in the present instance, by public service. It is to be noted that the pump may be operated by either of the motors alone or by both motors combined, 105 without disturbing the connection between the regulator and the throttle 20 and rheostat 41, the regulator 21 thus serving to control the supply of steam and the supply of electricity singly or in combination. 110

It has been pointed out that all the mechanical connections of the transmitting mechanism may remain connected when the electric motor is operating alone, as well as when it is operating in conjunction with the steam engine. The only condition under which it is necessary to interrupt such mechanical connection is when the steam engine is operating alone, and in such case it is a simple matter to withdraw the connecting stud 39 and remove the connecting rod 38 from the path of the crosshead. 120

I claim:

1. The combination with a pump, of a steam engine for operating the same, an 125 electric motor for operating the pump, operating connections between the pump and said engine and motor, a valve for controlling the supply of steam to the engine, a controller for the current whereby said mo- 130

tor is driven, a regulator influenced by the pressure developed by the pump, and connections between said regulator and said valve and controller whereby the motive forces for said engine and motor are automatically turned on and off.

2. The combination with a pump, of a steam engine for operating the same, an electric motor for operating the pump, operating connections between the pump and said engine and motor, a regulator influenced by the pressure developed by said pump, means actuated by said regulator for turning on and off the supply of steam for said engine, and means actuated by said regulator for turning on and off the current for said motor.

3. The combination with a pump having a reciprocating piston and piston rod, a steam engine operatively connected with said piston rod to drive the same, an electric motor, disconnectible means for transmitting motion from said motor to said piston rod, a regulator influenced by the pressure developed by said pump, means adapted to be actuated by said regulator for turning on and off the supply of steam for said engine, and means adapted to be actu-

ated by said regulator for turning on and off the current for driving said motor.

4. The combination with a pump having a cylinder, piston, and piston rod, of a steam engine having a steam cylinder and piston, said steam piston being operatively connected with said piston rod, an electric motor, a crank connected to said motor to be driven thereby, a connecting rod one end of which is engaged with said crank, disconnectible means for connecting the other end of said connecting rod with said piston rod, a regulator influenced by the pressure developed by said pump, means adapted to be actuated by said regulator for turning on and off the supply of steam for said steam engine, means adapted to be actuated by said regulator for turning on and off the current for said motor, and means for opening and closing communication between said steam cylinder and the atmosphere.

In testimony whereof I have affixed my signature, in presence of two witnesses.

WILLIAM T. PIERCE.
